CLOSURE

Fritz S. Zaisser, Bronx, N. Y.

Application September 22, 1933, Serial No. 690,535

9 Claims. (Cl. 156—14)

This invention relates to closures, especially closures for windows of buildings, and particularly closures consisting largely of a sheet of pervious material supported by a skeleton frame.

- 5 A principal object of this invention is the provision of a closure of the type indicated which will form a complete closure of an open window so that there will be an opportunity at no point for insects to pass.
- 10 A further object of the invention is the provision of a closure of the type indicated which is so constructed and applied that it may be readily shifted in position to allow one to protrude a portion of the body through the window opening in order to more readily view the outside, and which may be readily entirely removed.
- 15 A further object of the invention is the provision of a closure of the type indicated which is so constructed that it offers a minimum obstruction to light, air, and view.

20 A further object of the invention is the provision of a closure of the type indicated which is so constructed that it is readily adaptable to window frames of standard dimensions with slight variations therein, that is, variations not exceeding the generally allowable tolerance.

25 Other objects and advantages will appear as the particular physical embodiments selected to illustrate the invention, reference will be had to the accompanying drawings, and the several views thereon in which like characters of reference designate like parts throughout the several views, and in which:

- 30 Figure 1 is a front elevational view of a window, window frame, and a closure of my construction in place therein; Fig. 2 is a vertical sectional view on the plane indicated by the line II—II of Fig. 1, viewed in the direction of the arrows at the ends of the line; Fig. 3 is a horizontal sectional view 35 on the plane indicated by the line III—III of Fig. 1, viewed in the direction of the arrows at the ends of the line; Fig. 4 is a fragmentary horizontal sectional view on the plane indicated by the line IV—IV of Fig. 1, viewed in the direction 40 of the arrows at the ends of the line; Fig. 5 is a modified form of construction applicable to the closure of Fig. 1; Fig. 6 is a fragmentary perspective view of the left hand edge of the closure as shown in Fig. 1; Fig. 7 is a perspective view of 45 a parting strip attachment forming a part of the construction of the device as shown by Fig. 1; Fig. 8 illustrates the method of applying the closure to a window; Fig. 9 illustrates a modified form of closure; Fig. 10 is a perspective view illustrating the parting strip attachment means of

50 the form as shown by Fig. 9; Fig. 11 illustrates another form of window closure; Fig. 12 is a horizontal cross-sectional view on the line XII—XII of Fig. 11, viewed in the direction of the arrows at the ends of the line; Fig. 13 illustrates another modified form of screen and window attachment; Fig. 14 illustrates the parting strip attachment usable with the form of closure as shown by Fig. 13; Fig. 15 is a perspective view illustrating another form of parting strip attachment for the closure as illustrated by Fig. 1.

55 In Figs. 1 to 4 inclusive, a window frame 1 is shown having the inner sash 2 and the outer sash 3 and the parting strips 4. The sashes 2 and 3 are movable upwardly and downwardly 60 in the usual manner in the grooves 5 and 6.

65 In order to apply applicant's closure to a window frame the parting strip, or window frame side attachment, designated as a whole by P, Fig. 7, is first applied preferably to the parting strip. This is done by inserting ordinary round head wood screws, as 7, 8 and 9 at the proper positions therein to cooperate with the slotted orifices 10, 11 and 12 in the parting strip attachment. The screws are inserted so that a 70 slight space exists between the inner side of the head and the parting strip, just sufficient to receive material 13 of the thickness of the parting strip attachment. After the screws have been properly inserted, parting strip attachment P is 75 positioned in line with the parting strip and over the screw and the heads of the screws passed through the larger portion of the slotted orifice and then the parting strip attachment P is 80 pushed downwardly so as to bring the shank of the screws within the narrow slots of the parting strip orifices. This secures the parting strip attachment P securely but removably to the parting strip.

85 The parting strip attachment P is preferably 85 made of metal, and preferably of a non-rusting metal. It is of the thickness as above described and of a width no greater than that of parting strip 4. The upper end of the parting strip attachment P is strengthened by any appropriate 90 construction such as by an enlargement or folding over as shown at 13^a in Fig. 7. This strengthened portion, or bumper is provided as a stop for the lower rail 14 of the upper sash so that when it is lowered while the closure is in place 95 it will be stopped before coming in contact with the fragile parts of the closure.

100 The parting strip attachment P is also provided with a wing 15 for a greater portion of its length which acts as an abutment to prevent 105

110

outward movement of the somewhat fragile skeleton closure frame, and also serves as an insect shield for the space adjacent the edge of the closure.

5 At the foot of the parting strip attachment P a sideway slide preventer 16 is provided. This sideway slide preventer 16 is preferably formed integral with the parting strip attachment P by bending the metal to form substantially a closed 10 channel with a slot 17 in one face thereof. This construction at the bottom of the parting strip attachment, I term a sideway slide preventer.

Near the top of the parting strip attachment P, I position an oscillatable combined sideway 15 slide preventer and slide channel 18. This slide channel 18 is preferably formed of metal and is in substantially the form of a channel with a portion of one side 19 bent at a right angle to cause it to act as a sideway slide preventer.

20 In the base 20 of the channel a through bore 21 is provided which cooperates with a bore 22 in the parting strip attachment P to receive a rivet which holds the member 18 in place upon the parting strip attachment P, but allows it to 25 oscillate as rivet 23 is not headed tightly against the parts.

The parting strip attachments P are made right handed and left handed as shown by Fig. 1, and a left hand attachment is positioned on 30 the left hand parting strip as viewed in Fig. 1, and a right hand parting strip attachment is attached to the right hand parting strip as viewed in Fig. 1 with the sideway slide preventers opening toward each other.

35 After the parting strip attachments have been properly positioned on the parting strips the skeleton frame carrying the previous material is then to be positioned in its proper place.

The skeleton frame carrying the previous material is preferably formed of metal and in substance consists of a rectangular frame 24 formed of channel material and securely joined at the corners or made substantially integral as by welding. Within this frame the previous material 40 25 is secured. Both vertical edges of the frame are provided with members for cooperating with the sideway slide preventers of the parting strip attachments. These members, which I shall call flange members, are virtually extensions of the 45 vertical side channels and are designated 26. Each is virtually a channel having one leg 27 of the channel positioned within the sideway slide preventers, the face of the channel being received by the slot 17 of the bottom sideway slide 50 55 preventer and the slot 28 of the combined oscillating slide channel and the sideway slide preventer 18.

With a closure frame as described, placement in the window is affected by oscillating the members 18 to the position as shown in Fig. 8, then the flanges 27 are slid into the members 18 so that the frame is in the position designated, First Position in Fig. 8, then the closure is swung on the pivot formed by rivet 23 to the position designated Second Position in Fig. 8, and then the closure is allowed to drop so that flange 27 enters the bottom sideway slide preventer so as to assume the position designated Third Position in Fig. 8. When the closure has assumed the Third Position 60 65 70 75 the parts are in their final position and the window opening is completely closed against the entrance of insects because the bottom of the frame rests upon the sill, the top of the frame is almost in rubbing engagement with the lower rail of the inner sash and the space between the sides of the

frame and the parting strips is securely closed by the wing members 15 and the bottom sideway slide preventer and the upper slide and sideway slide preventer.

When the closure is in place, not only is the window opening completely closed to the entrance of insects, but the closure itself is so secured that no ordinarily blow will displace it. At the same time, if one desires to secure a better view of the outside, it is necessary only to reverse the operations of placing the closure frame in the window to the point where it assumes the First Position as shown in Fig. 8, whereupon part of the body may be protruded from the window to procure a better view of the outside or to raise or lower an awning or perform a similar task. If it is desired to completely remove the closure, it is only necessary to complete the reverse operations by withdrawing the rectangular frame from the window by the oscillating members after it has reached 95 the First Position.

Window frames as ordinarily constructed are generally of standard widths, that is, window frames come in sizes which vary by fixed amounts so that the distance between parting strips of 100 various size windows is a standard. There is however some variation in manufacture, that is, there is some tolerance allowed, and furthermore window frames shrink and swell. It is necessary to provide for all of the above mentioned variations. 105 This is very nicely done in applicant's construction because the flange 27 has an allowable movement within both the upper oscillatable slide preventer and the lower sideway slide preventer, so that not only is variations in width of sizes amply 110 provided for, but in addition, the frame is so held that even if the distance between parting strips is the very maximum, the rectangular frame will not separate from the parting strip attachment on either side because it will be prevented by the 115 flange 27 coming in contact with the right angle bend 29 of the bottom sideway slide preventer and the right angle bend 19 of the oscillatable slide.

Although applicant has illustrated his preferred form of mounting the top oscillatable slide 120 18 in Fig. 7, nevertheless, it may well be that an alternative form such as is shown in Fig. 15 may be of better service. This alternative form of slide 18 is pivoted on a pin 30 which passes through two folded over portions 31 and 32 of 125 member 15 and a folded over portion 33 of the sideway slide preventer 18.

In Fig. 5 applicant has illustrated a modified form of sideway slide preventer. This form of construction is applicable both to the bottom sideway slide preventer and the upper oscillatable sideway slide preventer. This construction includes two mutually cooperating corrugated parts. The vertical side piece 34 of the closure is extended into a corrugated side piece 35 which fits 135 between corrugated arms 36, forming a tortuous passage of a bottom sideway slide preventer 37 corresponding to 16. With this form of construction there may be considerable allowable variation between parting strips, and the rectangular 140 frame will be securely held against sideway sliding, because when the screen is positioned in the First Position as shown in Fig. 8, when the corrugated sideway slide preventer is used, those corrugations will be inter-fitted which are suitable for the particular distance between parting strips exhibited by the window, and when the frame is dropped to the final or Third Position, the proper corrugations will be inter-fitted so that 145 the rectangular frame will be suitably positioned. 150

In Fig. 9 applicant has illustrated a modified form of closure. In this form the parting strip attachment is designated as a whole by P'. It consists virtually of an angle having, in one leg, 6 orifices, as 38, by which it may be attached to a parting strip. The other leg of the angle is bent over both at the top and at the bottom to form a channel 39 to receive the rectangular frame 40 carrying the pervious material. In this form of 10 construction screws are properly attached to each of the parting strips and parting strip attachments P' are placed on the rectangular frame 40 and then the orifices 38 are engaged with the screws of the parting frame. In this form of construction variations of width are provided for by 15 the channels 39 of the parting strip attachment P'. These allow relative sliding movement between the rectangular frame 40 and the parting strip attachments but the window opening is completely closed because of the leg 41 of the parting strip attachment bearing against the side strips of the rectangular frame 40.

A further modified form of closure is shown in Figs. 11 and 12. This form is particularly applicable to closures of a dimension from the top to the bottom such that it may be placed in a window without interference by the upper sash. In this form, parting strip attachments P² are attached to the parting strips and the 20 rectangular frame for holding the pervious material is made just as is the rectangular frame of Fig. 1. This frame is put in position, however, by raising the frame to such a height that the bottom is even with the top of the parting strip attachments P², then the frame is slid downwardly with the flanges 27 engaged within the parting strip attachments.

In Figs. 13 and 14 another form of closure is illustrated. This differs from that in Figs. 11 40 and 12 in that the parting strip attachments differ. In this alternative form, the parting strip attachment designated as a whole by P³ is made in two parts, an upper part 42 and a lower part 43. The upper part 42 is pivoted, as by a screw 44, to the parting strip, and the lower part 43 is pivoted, as by a screw 45, to the parting strip. The rectangular frame carrying pervious material is made in the same way as the frame shown in Fig. 1. It is inserted by moving the 50 parting strip fittings to the light line positions as shown in Fig. 14. When the upper parting strip fitting 42 is turned into the light line position, as shown in Fig. 14, the rectangular frame may be slid into it and when it has reached the proper position the parting strip attachment may be made substantially vertical by pivoting upon the screw 44, and then the frame dropped into the lower portion 43 of the parting strip attachment P³. When the frame has been dropped to its lower position it serves to prevent pivoting of the members 42 and 43.

Applicant's construction is particularly applicable for fabrication from metal but applicant wishes it to be understood that although metal is preferred it is not at all necessary that metal be used, as the several parts may be equally well made of other material, such as wood.

Most of the forms shown are such that when in place the lower sash may be raised and lowered 70 at will without disturbing the closure. The upper sash may only be lowered to such position that its lower rail contacts with the top of the parting strip attachment.

In all of the forms shown the entire window 75 space is unobstructed except for the slight ob-

struction offered by the side pieces of the rectangular frame and the bottom rail of the rectangular frame. The top rail of the rectangular frame offers no more obstruction than the lower rail of the inner sash.

Although I have particularly described particular physical embodiments of my invention and explained the construction, principle, and mode of operation thereof, nevertheless, I desire to have it understood that the forms selected are merely illustrative, but do not exhaust the possible physical embodiments of the idea of means underlying my invention.

What I claim as new and desire to secure by Letters Patent of the United States, is:

1. In a window closure, in combination: a substantially rectangular frame supporting a sheet of pervious material, said frame provided with flanges on each of two opposite edges; and channels adapted to be attached to the parting strips of a window frame and opening toward each other for slidably receiving said flanges and for limiting movement of each of the flanges toward the opposite parting strip.

2. In a window closure, in combination: a rectangular frame supporting a sheet of pervious material; sideway slide preventers formed with a tortuous opening adapted to be attached to the opposite parting strips of window frames of somewhat varying width; and means attached to each of two opposite edges of the rectangular frame for cooperation with the said sideway slide preventers whereby the frame is held from sidewise motion notwithstanding varying window frame widths.

3. In a window closure, in combination: an attachment for a parting strip of a window including means for attachment to a parting strip, upper and lower sideway slide preventers, each substantially in the form of a channel having the opening closed except for a slight slot, and an abutment above the upper sideway slide preventer adapted for contacting the lower rail of the upper sash of a window.

4. In a window closure, in combination: a parting strip attachment, for a side of a window, including lower and upper sideway slide preventers, the upper sideway slide preventer mounted on a pivot whereby it may oscillate; a substantially rectangular frame bearing a sheet of pervious material and provided on each of two opposite edges with flanges whereby when the upper sideway slide preventer is oscillated in one direction one of said flanges may be inserted therein and slid endwise thereof in one direction and then after oscillation in an opposite direction of the upper sideway slide preventer the frame may be slid into the associated lower sideway slide preventer whereby the rectangular frame is securely maintained in the window, the sidewise slide preventers being formed with facing openings forming a tortuous passage and the flanges being corrugated whereby the frame may be fitted to window frames of varying widths.

5. In a window closure, in combination: a parting strip attachment adapted to be attached to the parting strip of a window for a side of a window, including lower and upper sideway slide preventers, the upper sideway slide preventer mounted on a pivot whereby it may be oscillated; and said attachment comprising a base and a wing positioned when attached at a right angle thereto; a substantially rectangular frame bearing a sheet of pervious material and provided on each of two opposite edges with flanges where-

by when the upper sideway slide preventer is oscillated in one direction one of said flanges may be inserted therein and slid endwise thereof in one direction and then after oscillation in an opposite direction of the upper sideway slide preventer the frame may be slid into the lower sideway slide preventer whereby the rectangular frame is securely maintained in the window, and whereby the opening made by raising the lower sash is completely closed against insects if the lower sash is not raised higher than the rectangular frame.

6. In a window closure: in combination: a substantially rectangular frame bearing a sheet of pervious material, said frame on each of two opposite edges formed with corrugated extending arms with the grooves of the corrugations running parallel with the edges; means for attachment to the opposite parting strips of a window for receiving the said corrugated arms for securing the rectangular frame in place in a window frame whereby variations of standard dimensions of window frames is provided for.

7. In a window closure, in combination: a substantially rectangular frame bearing a sheet of pervious material, said frame on one of its edges formed with a corrugated extending arm with the grooves of the corrugations running parallel with the edge; a channel formed with a tortuous opening for attachment to one side of a window frame and opening toward the opposite side of the window frame for receiving the said corrugated arm for securing the rectangular frame in place in a window frame whereby variations of standard dimensions of window frames is provided for.

gated arm for securing the rectangular frame in place in the window frame whereby variations of standard dimensions of window frames is provided for; and means for supporting and slidably attaching the edge of the rectangular frame opposite to and parallel to the first mentioned edge to the side of the window opposite to that to which the channel is attached.

8. As a window closure, the combination of a rectangular frame supporting a sheet of pervious material, formed along one edge with a corrugated extending arm with the corrugations running parallel with the edge whereby the closure is adapted for window frames of varying widths when provided with means for receiving and holding the corrugated arm and the opposite parallel edge of the frame.

9. In a window closure, in combination: a rectangular frame supporting a sheet of pervious material, said frame on one edge formed with a corrugated extending arm with the corrugations running parallel with the edge; means attached to one side of a window frame for receiving and holding the corrugated arm when the edge of the rectangular frame is at varying distances from the window frame; and means for attaching and holding the edge opposite and parallel to the first mentioned edge to the side of the window frame opposite to that to which the corrugated arm is attached.
